By Rogers, Kennedy & Campbell
ATTYS.

UNITED STATES PATENT OFFICE.

JOHN GLENNIE HOLBOURNS, OF LONDON, ENGLAND, ASSIGNOR TO LINOTYPE AND MACHINERY LIMITED, OF LONDON, ENGLAND, A LIMITED LIABILITY COMPANY OF GREAT BRITAIN.

MECHANICALLY-CAST TYPE-BAR.

1,306,902.

Specification of Letters Patent. Patented June 17, 1919.

Application filed February 28, 1919. Serial No. 279,834.

To all whom it may concern:

Be it known that I, JOHN GLENNIE HOLBOURNS, a subject of the King of the United Kingdom of Great Britain and Ireland, and 5 residing at 188 and 189 Fleet street, in the city of London, England, have invented new and useful Improvements in or Relating to Mechanically-Cast Type-Bars, of which the following is a specification.

10 This invention relates to mechanically cast type bars and has for its object to cast these devices in such form that they can be locked together in pairs, as for example, may be necessary in type bars intended to print a 15 person's name and his address in two parallel lines.

There has recently been a demand for cast type bars of this description, particularly for use in inserting names and addresses in 20 dividend warrants and the like, because, with the means heretofore available, considerable time has been involved in composing the separate letters of the name and address into a metal holder, and because when 25 so composed, displacement or transposition can readily occur, with the result that a stockholder's name may be presented with an incorrect address or vice versa.

The present invention aims at providing 30 cast type bars, hereinafter called slugs, which shall be interlocked together in pairs, one slug bearing say the name of a stockholder, and the other say his address. For this purpose, one slug is provided with a 35 dovetail or equivalent recess which receives a dovetail or equivalent projection cast on the other or complementary slug. If desired, these projections may be cast with a slight flare so that the slug provided with 40 the recess will prevent any movement of the other slug in the direction of height to paper.

The type of slug to which the present invention more particularly relates, is one of 45 very shallow depth in the direction of height to paper, and may be cast in a typographical composing or casting machine known commercially under the trade mark "Linotype". For this purpose the mold wheel of that machine would be provided with two molds, of 50 which the face of one would be recessed to cast the slugs with the dovetail recesses, and the face of the other would be recessed to cast the complementary slugs with the pro-

jections which fit into the said dovetail recesses of the first named slugs. 55

The invention will now be more particularly described by reference to the accompanying drawings in which:—

Figures 1 and 2 are perspective views 60 showing one construction of the two complementary slugs according to the said invention, these slugs being represented integral with jets or sprues such as are ordinarily produced when the slugs are cast in the before-mentioned typographical composing and casting machine. 65

Fig. 3 is a perspective view showing the same two slugs as those represented in Figs. 1 and 2 with the sprues detached, and interlocked in printing condition, and 70

Fig. 4 is a perspective view similar to Fig. 3, but showing a modified form of complementary slugs in interlocked and printing condition. 75

Like reference numerals are used to indicate like parts in both of the arrangements illustrated in the drawings.

As hereinbefore stated, the particular slugs to which the present invention relates, 80 are intended to be associated and used in pairs, one slug bearing say the stockholder's name and the other slug bearing say the stockholder's address.

Fig. 3 represents such a pair of slugs 85 which latter in that figure, and in the separate representations shown in Figs. 1 and 2, are respectively identified by the numerals 1, 2.

The slug 1 is formed with the dovetail or 90 equivalent recess 3, and the slug 2 with a dovetail projection 4 adapted to fit snugly into the recess 3 as shown in Fig. 3, so as, in effect, to lock the two slugs together.

Each of the slugs 1, 2, as indicated dia- 95 grammatically in the drawings, has the usual line 5 of printing characters (herein- after termed a printing line) so positioned thereon that when the two complementary slugs are interlocked as shown in Fig. 3, the 100 two printing lines 5 thereof will be parallel and at the required distance apart.

The sprues 6 shown in dot-and-dash lines in Figs. 1 and 2 are the parts which are formed within the mold of the typographical line-casting machine, and these by sawing or otherwise, are afterward detached from the slugs 1 and 2, which latter are then 105

left in the shallow form in which they may be readily locked together in the manner represented in Fig. 3.

The printing lines 5 are, as ordinarily, 5 cast in the formative cavities of a line of matrices assembled in order of composition, while the remaining portion of each slug is formed in a recess in the face of the mold, and the printing lines may be cast on the 10 respective slugs in any desired position according to the space required to be left between the printing lines of each pair of interlocked slugs.

The shape of the interlocking dovetails 15 may be varied and, as an example of one such variation, Fig. 4 shows an arrangement wherein two interlocking dovetails 7 are provided, one near each end of the pair of slugs, this, as distinguished from the arrangement illustrated in Figs. 1, 2 and 3, wherein a single dovetail extends practically throughout the length of the slugs; the said shape may however be varied in other respects for example, instead of the 25 dovetails being of rectangular form as illustrated in the drawings, their edges may be inclined or curved.

The different pairs of interlocked slugs constructed as aforesaid, when used for 30 printing, are fitted in a suitable carrier by which they can be presented in printing position in the desired order.

Copies of this patent may be obtained for five cents each, by addressing the "Commissioner of Patents, Washington, D. C."

Having described my invention, I declare that what I claim and desire to secure by Letters Patent is:—

35

1. As a new article of manufacture a cast type bar provided with means cast integral therewith and by which it can be locked to an adjacent type bar.

2. As a new article of manufacture a pair 40 of cast type bars provided with mutually engaging means cast integral therewith by which they can be locked together.

3. As a new article of manufacture a pair of cast type bars of shallow depth in the 45 direction of height to paper, one of such type bars being provided with a single dovetail projection, and the other of such type bars being provided with a single dovetail recess adapted to receive the said projection 50 so as to lock the two type bars together.

4. As a new article of manufacture a pair of cast type bars of shallow depth in the direction of height to paper provided with a plurality of dovetail projections on one of 55 the said type bars, and a plurality of dovetail recesses in the other of such type bars, the said recesses being adapted to receive the dovetail projections so as to lock the two type bars together.

60

In testimony whereof I have affixed my signature hereto.

JOHN GLENNIE HOLBOURNS.
